UNITED STATES PATENT OFFICE.

CLYDE SHEPPARD, OF LOS ANGELES, CALIFORNIA.

SMOKER'S ASH AND SPARK PROTECTOR.

Application filed December 13, 1923. Serial No. 680,490

To all whom it may concern:

Be it known that I, CLYDE SHEPPARD, a citizen of the United States, residing at Los Angeles, in the county of Los Angeles and State of California, have invented certain new and useful Improvements in a Smoker's Ash and Spark Protector; and I do hereby declare the following to be a full, clear, and exact description of the invention, such as will enable others skilled in the art to which it appertains to make and use the same.

This invention relates to a protector for cigars and cigarettes.

It is aimed to provide a construction which will efficiently prevent the falling of ashes or flying of sparks from the cigar or cigarette to particularly avoid damage to the clothing of the smoker.

Another object is to provide a construction in which the cigar is spaced from the wall of the protector and sufficient draft is afforded.

A third object is to provide a construction in which the protector has depressions to space the cigar from its wall as aforesaid and in which the depressions have vent openings so located as to prevent the escape of ashes.

A further object is to provide a novel means whereby the protector may clasp the cigar or cigarette and which will permit, if desired, the use of an ordinary mouth piece or holder.

A fifth object is to provide a construction in which the protector has a removable cap or the like to facilitate insertion and removal of the cigar, cigarette, or butts and in order to facilitate lighting of the cigar or cigarette.

Various additional objects and advantages will become apparent from a consideration of the description following taken in connection with the accompanying drawings illustrating the operative embodiment.

In said drawings:—

Figure 1 is an elevation of the device as used in connection with a cigar and with a mouth piece or holder attached;

Figure 2 is a substantially central longitudinal sectional view of the form shown in Figure 1 and with a cigar in place;

Figure 3 is a view similar to Figure 2 but omitting the mouth piece or holder;

Figure 4 is a perspective view of the parts making up the protector and with the same in disassociated relation;

Figure 5 is a cross sectional view taken on the line 5—5 of Figure 1;

Figure 6 is an enlarged view in perspective illustrating the lugs of the protector;

Figure 7 is a view similar to Figure 2 but showing a form somewhat modified and as used in connection with a cigarette, and

Figure 8 is a perspective view of the modified form of cap as used in Figure 7.

Like reference characters designate like and similar parts in the different views.

Referring first to the form of Figures 1 to 6, the protector consists of a substantially tubular barrel which at its front end as at 11 has detachable connection with a cap 12, as by means of a friction joint. The parts 10 and 12 are preferably made of a suitable metal but of course may be made of any desired material. At the rear end, barrel 10 is longitudinally split as at 13 to provide clasp fingers 14 adapted to engage and grip the article to be smoked, in this instance, a cigar 15. The fingers 14 are preferably longitudinally curved as shown and deflected inwardly at their distal ends and are contractile.

In order to provide draft for the cigar 15, the forward end or tip of the cap 12 is perforated in order to provide multitudinous vent openings 15'. The barrel 10, and also the cap 12 if desired, have inward depressions forming spacing lugs 16 serving to locate the cigar out of contact with the walls proper of barrel 10 and cap 12. The surfaces of the lugs 16 which engage the cigar are preferably arcuate as at 17. These lugs 16 also have side walls as at 18 through which vent openings 19 are provided. The vent openings 19 are preferably located inwardly a distance from the side walls of the barrel and cap to the end that ashes falling into engagement with such walls or sparks, cannot escape through said openings.

The interior of the tubular barrel 10 is provided near its rear end, adjacent to clasp fingers 14, with a band 20 made of cork or other suitable material, and secured thereto in any preferred manner. The purpose of band 20 is to frictionally grip and retain the cigar within the protector against accidental movement independently thereof.

The butt end of the cigar projects a considerable distance in the rear of the fingers 14 so that the cigar may be placed in the mouth and smoked in the usual manner as

suggested in Figure 3. When the cigar is to be lighted or a butt is to be removed or discharged, the cap 12 is removed from the barrel.

6. If desired, the resilient clasp action of the fingers 14 in engagement with the cigar may be augmented by an annular metallic lock band 21 which surrounds the fingers and by movement along them, due to their 10 curvature, a substantially cam action is obtained which compresses the fingers into the cigar and automatically holds them in that position. While the band 20 may usually be used, yet at the present time it is generally omitted unless a mouth piece or holder, as shown in Figures 1 and 2, in particular, at 22 is also used. This mouth piece may be of any desired material for instance metal, amber or the like and may be an ordinary 15 one purchased in the open market, so that the use of my invention will not preclude the use of the ordinary mouth piece or holder. This holder is preferably flared at the forward end so as to increase the size of its 20 bore and the latter removably receives the rear end of the barrel 10, particularly the fingers 14 and the band 21, specifically frictionally engaging the band 21 and thus forming a secure connection. The holder 25 22 also receives the butt end of the cigar.

The invention is not limited to use in connection with a cigar but may be adapted for use with cigarettes, as indicated in Figure 7, in which 23 designates a cigarette. The 25 construction of the parts in this form is substantially the same as in the preceding figures, the only exception being the cap, designated 12^a, which has a flat top, as shown in Figure 8, to conform to the shape of the 30 end of a cigarette as distinguished from the pointed cap in the remaining views of the drawings.

Various changes may be resorted to provided they fall within the spirit and scope 35 of the invention.

Having thus described the invention, what I claim is:—

1. A protector to enclose the lighted end of a cigar or cigarette and having vent means

therethrough, and means spacing the cigar 50 or cigarette from the inner wall of the protector, consisting of inwardly depressed portions having openings inwardly of said wall and through their sides for ventilation.

2. A protector to enclose the lighted end 55 of a cigar or cigarette, the protector having inwardly extending means to space the cigar or cigarette from the side wall of the protector, and vent means laterally through the said means opening inwardly of the said 60 wall.

3. A protector to enclose the lighted end 65 of a cigar or cigarette and having vent means therethrough, the protector having clasp fingers to engage the cigar forwardly 70 of its butt end, a pressure band slideable over said fingers, and a holder to receive the butt end of the cigar and frictionally engage said band.

4. A protector to enclose the lighted end 75 of a cigar or cigarette and having vent means therethrough, clasp means to engage the cigar or cigarette located at the rear end of the protector and forwardly of the butt end of the cigar or cigarette, and a holder applicable over said butt end and frictionally engageable with said clasp means.

5. A protector to enclose the lighted end 80 of a cigar or cigarette, the same consisting of a barrel, a cap detachably connected to said barrel, said cap and barrel having vent openings therethrough, said barrel having inwardly depressions engaging the cigar or cigarette and spacing it from the inner wall thereof, the vent openings of the barrel being located through the side walls of said depressions and inwardly of said inner wall, a grip band to engage the cigar or cigarette located within the barrel, and the rear end of the barrel terminating in resilient clasp fingers to engage the cigar or cigarette.

In testimony whereof I affix my signature in presence of two witnesses.

CLYDE SHEPPARD.
